LEAD ALLOY

François Cuveliez, Hoboken-lez-Anvers, Belgium,
assignor to Société Générale Metallurgique de
Hoboken, Hoboken - lez - Anvers, Belgium, a
Belgian limited company

No Drawing. Original application August 2, 1938,
Serial No. 222,670. Divided and this applica-
tion February 9, 1939, Serial No. 255,509. In
Great Britain October 15, 1937

1 Claim. (Cl. 75—167)

This application is a division of my application
Ser. No. 222,670 filed August 2, 1938.

This invention relates to lead alloys to be used
in the chemical industry.

5 A lead alloy according to the present invention
is of the usual compact, non-porous, structure,
and comprises from 0.3 to 13% Sb and from 0.2
to 5% Hg.

Moreover, the alloy contains one or more of
10 the metals Zn, Ca, Bi:

	Per cent
Zn	0 to 0.6
Ca	0 to 0.1
Bi	0 to 1, the rest being lead

15 The non-porous alloys according to the present
invention not only resist corrosion by chemical
agents, more particularly of sulfuric acid and

nitrous gases, as is the case with sulfuric acid
plants of the chamber method type, but in addition
they have also a high resistance to mechanical
and physical efforts.

The alloy according to the present invention 5
has a compact structure, such as industrial alloys
generally have when they are made by the known
processes of casting, moulding or rolling.

I claim:

A compact lead alloy to be used more par- 10
ticularly against corrosion by chemical agents,
consisting of from 0.3 to 13% of antimony, from
0.2 to 5% of mercury, from 0.1 to 0.6% of zinc,
from 0.005 to 0.1% of calcium and from 0.2 to 1% 15
of bismuth, the rest being lead.

FRANÇOIS CUVELIEZ.
